UNITED STATES PATENT OFFICE.

NORMAN T. WHITAKER, OF NEW YORK, N. Y., ASSIGNOR OF ONE-FOURTH TO HARRY F. LOWENSTEIN, OF WASHINGTON, DISTRICT OF COLUMBIA.

TELEPHONE-EXCHANGE SYSTEM.

Application filed April 4, 1916, Serial No. 88,832. Renewed February 2, 1922. Serial No. 533,673.

To all whom it may concern:

Be it known that I, NORMAN T. WHITAKER, a citizen of the United States, and resident of New York, in the county of New York 5 and State of New York, have invented new and useful Improvements in Telephone-Exchange Systems; and I hereby declare the following to be a full, clear, and exact description of the invention, such as to enable 10 others skilled in the art to make and use the same.

My invention relates to telephone exchange systems and more particularly to a signaling system to enable two connected 15 subscribers to be notified that a certain party desires to be connected with either of them, and further to notify the third party that the line called is busy and has been notified of the second desired connection.

20 It is often the case that when two subscribers are conversing on a wire that a third person desires to be connected with either of the two who are talking. My invention seeks to overcome this by the provision of signals situated at the subscribers' 25 stations, adapted when two of said subscribers are connected, to be controlled through means associated with the cord circuit of the same or a second operator through 30 which the third party wishes to call the connected parties.

Another important object of the invention 35 is as follows: When a party desires to get either of two subscribers who are talking on a telephone circuit, he is at the present time told that the other party is busy. This entails work and time upon the operator and my invention seeks to overcome this by directly signaling said party who desires to 40 be connected as soon as the operator herself knows that the wanted party is busy. No new signaling means is used, simply the means which my system already provides for with each and every telephone.

45 My system has certain desirable results as follows: It would be an advantage to two subscribers when they are conversing to know that some one else desires to talk with them. They would in all probability shorten 50 their conversation to enable the third party to get connection. This is furthermore advantageous to the party who desires to talk to the two subscribers, thus preventing much annoyance and inconvenience when he is 55 told that the wire is busy. Furthermore, my

system is of advantage to the telephone companies in that they are enabled to collect more revenue from the pay stations as frequently when one desires to call a party and is told that they are busy, he will simply 60 defer his call to a later time and possibly not call at all. Although this invention appears simple, it requires great skill to carry out the objects of the invention. While I have shown apparently complicated means 65 for accomplishing this much desired object, it would be found to be comparatively simple in construction and operation.

Various signaling means may be used to attract the attention of the connected subscribers that some one else desires to communicate with them, but I prefer that the signalling means be made visual as will be clearly pointed out, although the two subscribers could be notified by means of an 70 audible signal used in place of the visual signal. The visual signaling means could be either in the form of a flashing filament located in the telephone standard or nearby or could be by means which I have shown 75 which consists in a semaphore or flag pivotally mounted on the telephone stand which is controlled from the central station. I have preferably shown this signaling means connected to the stand of an ordinary telephone but it is obvious that this or other 80 signaling means could be applied to the telephone structures used in booths or in telephone wall attachments.

In reduction to practice, I have found that 90 the form of my invention, illustrated in the drawings and referred to in the above description as the preferred embodiment, is the most efficient and practical, yet realizing that the conditions concurrent with the adoption 95 of my device will necessarily vary, I desire to emphasize the fact that various minor changes in details of construction, proportion and arrangement of parts may be resorted to, when required, without sacrificing any of the advantages of my invention as defined in the appended claims.

Referring to the drawings in which similar parts are referred to by similar reference numerals,

Figure 1 represents a front elevation of one form of the subscribers signaling device.

Fig. 2 is a front view of the signaling device of Fig. 1, with the cover removed.

Fig. 3 is a fragmentary section through the standard of a desk-set telephone showing a modified form of signaling device.

Fig. 4 is a diagrammatic view of the 5 circuits of a telephone exchange system equipped with my signaling system.

Fig. 5 is a diagram illustrating a modification in which the signal is operated by a reversal of the battery supply current, in 10 the standard Western Electric circuit.

Fig. 6 is a similar diagrammatic view of the device applied to circuits of the Kellogg type.

Fig. 7 is a diagram illustrating a circuit 15 arrangement in which the signaling apparatus is actuated upon the testing of the line.

Now referring more particularly to the drawings and especially to Figs. 1, 2 and 3, 20 I have herein shown the signaling means, or responsive devices to be used at the sub-stations. In Figs. 1 and 2 I have shown an electromagnetic responsive device adapted to be used in either of two modified circuit 25 arrangements, to be hereinafter described, namely, one wherein the signal is actuated by an individual circuit and one wherein the signal is actuated by a reversal of the current in the line.

30 This apparatus is contained in a box 1 provided with a cover 2 and adapted to be mounted on a standard 4 of a desk-set by means of a split ring member 3, or other suitable attaching means, carried by the casing 1. Mounted within the casing 1 is a pair of electromagnets, 5, 6 having forwardly projecting cores 7, 8, which act on a rotary, polarized armature 9 journaled on an adjustable pivot 10, which pivot is carried 35 on a suitable bracket such as 11 which may be extended upwardly from the yoke of the magnet or otherwise rigidly mounted. The armature carries a staff 12, which projects through an arc aperture 13 in the cover 40 and is bent at right angles so as to lie close and parallel to the cover. The flag or semaphore 14 is carried on a staff and the parts so arranged in relation to each other that upon energization of the magnets 5 and 6, 45 the armature 9 will swing into a vertical position, positioning the flag as indicated in dotted lines in Fig. 1. As the armature 9 is polarized it will rotate in a counter-clockwise direction when the magnets are energized with a given polarity, but when energized in the opposite polarity the armature 50 will not rotate in a clockwise direction due to the limited downward extension of the arc of the aperture 13 limiting the downward 55 movement of the staff 12. In operating this signal by reversal of the current in the line the signal will remain set so long as the reversed condition maintains, which in the system here shown will be equal to the remaining length of the connection between 60

the subscribers. However, in a simplified form of the system, the signal is operated in an individual circuit momentarily closed and in order to have the signal remain set after the circuit is again opened, a retaining 70 spring 18 is provided on the cover 2 at the top thereof and positioned to engage the top of the staff 12 when the flag is thrown up into set position.

Referring in detail to Fig. 3, I have here 75 shown a portion of the standard of an ordinary desk set having an aperture 20 inside of which is mounted a small incandescent lamp 21. The lamp 21 fits into a socket 22 carried by the bracket 23 which in turn is 80 fixed to the wall of the standard 19 by a suitable screw such as 24. The bracket 23 is made circular in form where it contacts with the wall of the standard and carries an annular member 25 whose purpose is to 85 hold a glass cover 26 over the aperture 20 to protect the light and other parts within the standard from dust.

In Fig. 4 is shown diagrammatically, a 90 circuit arrangement of the Western Electric type in which is incorporated a simplified form of my signaling system. In this are shown two subscribers' stations C and D. The line wires 29 and 30 of the subscriber's station C terminate in the central exchange 95 in normally closed contacts controlled by the armatures 31 and 32 of the cut-off relay 33. The cut-off relay 33 has one terminal connected through wires 34, 35 and 67 to the positive side of the common battery B, while the other terminal of the cut-off relay is connected to the multiple of the sleeve contacts 83 of the multiple jacks 79 and 80. The armature 31 of the cut-off relay is connected to battery through conductor 34 100 105 while the armature 32 leads to one terminal of the line relay 36, the other terminal of the line relay being connected to the minus side of the battery by conductor 37. Multiple jacks, two, 79 and 80, of which are here 110 shown, extend from the line members 29 and 30 and consist each of a tip contact 81, ring contact 82 and sleeve contact 83. The line relay 36 controls the usual line lamp 38 through a normally open contact of the armature 39. At the subscribers' stations the usual switch hook S, transmitter T, and receiver R are provided, the switch hook S controlling the line circuit through the contact 40.

115 In addition to the standard subscriber's equipment, I provide the signal responsive device 43, here shown as a lamp, although I may also use in its place the electro-magnetic signal illustrated in Figs. 1 and 2. The 120 signal 43 has one terminal connected directly to ground and the other terminal connected to the tip side of the line through contacts 44 which contacts are adapted to be closed by the bridging member 45. 130

The apparatus and circuit arrangement of the substation D are in all respects similar to those of the substation C and the preceding description of apparatus and circuits 5 will therefore suffice for both substations.

The cord circuit here shown is of the standard Western Electric type with the exception that a key 96 is inserted in the calling tip conductor 60, for a purpose to be hereinafter described. This cord circuit consists of the usual answering and calling plugs, the answering plug having its tip 55 and ring 57 connected through the right halves 65 and 66 of one side of the repeating coil, 10 between which is connected the battery B over the conductors 67 and 68. Similarly 15 the tip 56 and ring 58 of the calling plug are connected over conductors 60 and 62 to the other two halves 63 and 64 of the repeating coil.

Included in the ring conductor of the cord circuit are the usual supervisory relays 69 and 70. The relay 69 controls the calling supervisory lamp 71 through a normally 25 open contact on the armature 721, which contact operates upon closure to connect shunting resistance 73 around the terminals of the lamp. The lamp is supplied with current from the battery B through conductor 68, the resistance 72, sleeve contact 286, the sleeve of the jack 83, through the cut-off relay 33 and back by way of wires 34 and 35 to the plus side of battery. The supervisory relay 70 controls the calling 30 supervisory light 74 in a manner similar in every respect to that of the answering supervisory relay, the light 74 being supplied with current from the minus side of the battery over conductor 68, resistance 78, conductor 97, sleeve contact 285, jack sleeve contact 85, conductor 76, cut-off relay 50, and conductor 35 back to the battery.

The usual ringing key 86 is provided which is adapted upon actuation to disconnect the cord circuit from the tip and ring of the plug and connect in its place a suitable source of alternating current for ringing purposes. The cord circuit, at the calling end, is also provided with the usual operator's listening and talking set for the purpose of conversing with the subscribers and testing the wanted lines.

The operation of the circuit apparatus in Fig. 4 is as follows: The subscriber at substation C desiring a connection with a subscriber D lifts his receiver off the hook whereupon the line circuit is closed over the following paths: Battery B, conductors 67, 35, 34, armature 31, line conductor 29, 42, 60 induction coil winding 41, switch hook contact 40, switch hook S, transmitter T, conductor 30, 32, line relay 36 and conductor 37 back to the minus side of battery B. As this circuit includes the windings of the line 65 relay 36, this relay is energized attracting its

armature 39 and completing the circuit of the line lamp 38 which notifies the operator that a connection is desired. The operator thereupon inserts the answering plug in the jack 79 whereupon the current flows from battery B, over conductor 68, resistance 72, supervisory lamp 71, sleeve contacts 286, 83, cut-off relay 33 and back by way of conductors 34 and 35 to the positive side of battery. As this circuit includes the cut-off 70 relay 33, this relay is energized attracting its armature and disconnecting the line wires from the line relay 36 to the battery conductor 34. This in turn opens the circuit of the line relay which releases its armature 39, extinguishing the line lamp 38. The substation C is now supplied with current over the following paths: Battery B, conductor 68, repeating coil winding 66, conductor 61, 57, 82, 30, transmitter T, switch hook contact 40, 41, 42, back over line conductor 29, jack spring 81, tip contact 55, conductor 59, 65, and back to battery through conductor 67. As the answering supervisory relay 69 is included in the conductor 61 over which this circuit was traced, this relay becomes energized, attracting its armature 72, which shunts out the supervisory lamp 71. The operator now actuates her listening key 87 which connects her listening and talking circuit set across the cord conductors 60 and 62. This talking set consists of receiver 89 connected across the terminals of the listening key 87 in series with condenser 94 and the secondary winding 92, the primary 91 of the induction coil being connected in series with a transmitter 88 and retardation coil 90 across the terminals of the battery. A condenser 93 is connected in shunt of the winding 91 and transmitter 88. With the listening set in connection the operator inquires the number desired and upon ascertaining the same to be that of the subscriber D, inserts the calling plug into the jack 77. A circuit is then completed over the following path: Battery B, 68, 78, 74, 97, 285, 85, 76, cut-off relay 50, conductor 51, 35, and back to battery. As this circuit includes the windings of the cut-off relay 50 and the light 74, both of 100 these are energized, the cut-off relay 50 acting to disconnect the line wires 46 and 47 of the called subscriber from the battery wire 51 and the line relay 52. The operator signals the called subscriber by actuating the ringing key 86 and when the called subscriber answers by raising his receiver, his line circuit is completed over the following path: Battery B, 68, 64, 62, 58, 84, 46, through the substation apparatus, back over line wire 47, jack spring 296, 56, 60, including the key 96, 63 and 67 to battery B. As this circuit includes the windings of the calling supervisory relay 70, this relay is energized attracting its armature 75 and plac- 105 110 115 120 125 130

ing the resistance 76' in shunt of the lamp 74 and extinguishing it. The extinguishing thus indicates to the operator that the called subscriber has answered and the parties are 5 now connected for conversation over the circuit indicated in lines.

If while the parties C and D are thus connected for conversation, a third party should desire to be connected with either one of 10 them, the line of said third party would become connected with the cord circuit of a second operator through her answering plug in a manner similar in all respects to that above described. The second operator ascertaining the number desired to be that of 15 the subscriber D, tests the line of that subscriber by touching the tip of the plug 56 to the sleeve contact of a multiple jack such as 295. As this line is already connected with, the sleeve contacts of all of its multiple jacks will be connected through the contact 285 of the first operator's calling plug to the minus side of the battery, current will flow from the plus side of battery over the 20 tip conductor of the second operator's cord circuit to the jack sleeve contact 295 and back to the minus side of battery by way of the plug sleeve contact of the first operator. This flow of current will vary the potential 25 across the receiver 89 of the second operator giving her a click in the ear which is the usual indication that the line is busy. Upon receiving such a signal the operator plugs in to the jack in the usual manner, but instead of operating the ringing key as 30 usually would have been done had the wanted subscriber's line been idle, she operates the special signaling key 96 which opens the conductor 60 and connects it on the calling side with the battery B'. Upon 35 closure of this connection, both the signals 43 and 280 at the stations between connected subscribers will be energized by current flowing over the following circuit: 40 Substation D from battery B' over conductor 60 of the second operator's cord circuit, tip contact 56, tip contact of the multiple jack 295, line conductor 47, switch hook contacts 281 and through signal 280 45 back to battery by way of ground, while for the substation C the current will branch at the jack 77 of the first operator passing therethrough by way of tip contacts 296, 56, of the operator's cord circuit, tip conductor 50 60, including the normally closed contact of key 96, repeating coil windings 63, 65, 59, 55, 79, 29, signal contacts 44, substation signal 43 and back to battery B by way of ground. It will thus be seen that each time the second operator operates the key 96 the lamps 65 43 and 280 will be flashed, and if the electro-magnetic signal device of Figs. 1 and 2 is used in place of the lamps, only a single momentary operation of the key 96 will be necessary as the first actuation of the signal

will cause it to remain in set position until restored by hand. It is further to be noted that if it is desired to use the lamp, and still obviate the necessity of the operator having to operate the key 96 more than once or for 70 any considerable time, the light may be combined with the device of Figs. 1 and 2, using the latter device as a relay to control the local circuit for the light. In such case, it is only necessary for the second or testing 75 operator to momentarily actuate the key 96 after which she may withdraw the plug and wait until the third party again initiates a call either through her or any other operator. It might be noted in passing that 80 with the batteries B and B' connected in opposition or multiple as here shown, the tip conductor of each line will be used in common by both the talking circuit and the signaling circuit, which arrangement is the 85 preferable one. However, it would not affect the operation of my device to reverse the polarity of the battery B'.

Referring to Fig. 5, I here show a modified method of control adapted to the Western Electric type of circuits. In this form of the invention, an electro-magnetic actuated, polarized signaling device is used at each substation inserted in one of the line conductors. To operate the signals at the 90 substations of the subscribers, it is only necessary to reverse the current in the line and for this purpose I have shown a simple form of pole changer relay 140 associated with the operator's cord circuit, although 95 it is to be understood that various other means of reversing the current may be used, such for instance as that shown in the patent to E. Thomson, No. 1,121,953 issued December 22, 1914, or to G. Babcock, No. 1,012,793, 100 issued December 26, 1911, such apparatus being either connected in place of the relay 140 or controlled by a relay in its place. The line circuits and terminal apparatus therefor are of the well known standard 105 type and therefore need no description, except to point out that the special polarized signaling means at each substation is inserted in one of the line conductors, for example, here shown in the tip conductor 110 with a condenser bridged across its terminals to compensate for any inductance in the windings of the electro-magnets. The relay 140 is provided with a pair of connected movable contacts or armature constituting 115 the movable members of a pole changer, which armatures 138, 139 are connected directly to the terminals of the battery B' over conductors 143 and 107, respectively. The inner contacts of the pole changer are connected together in the usual manner and lead through conductor 136 to the middle point of the upper windings of the repeating coil, while the outer contacts are connected together and lead through conductor 120 125 130

137 to the middle point of the lower windings of the repeating coil. In addition to the relay 140 the only other changes necessary in the standard circuit are to substitute 5 the windings of the relay 153 for the permanently connected resistance in the circuit of the calling supervisory lamp 150 and to add an extra pair of contacts on the calling supervisory relay 149. The relay 140 is 10 primarily controlled by relay 153 through a normally closed contact thereof. The initial energizing circuit of the pole changer relay 140 may be traced from battery B^2 over conductors 107, 106, 302, armature 154, 15 conductor 155, windings of relay 140, conductor 158, armature contact 297 and back to the grounded side of battery B^2 by way of conductor 104. As this circuit includes 20 a normally open contact controlled by the calling supervisory relay, the circuit of the pole changer relay will be maintained normally open and out of control of the relay 153 until after the called subscriber has answered, and as the circuit of the calling 25 supervisory light, which in this case includes the windings of the relay 153, is always closed immediately upon the insertion of the calling plug and before the subscriber answers, the circuit of the pole changer relay 30 will be opened at the contact of relay 153 before it is closed through the contact 297 by the actuation of the calling supervisory relay by the called subscriber's act of lifting his receiver. At the end of a conversation 35 when the called subscriber finally hangs up his receiver, the calling supervisory relay will be de-energized, thus opening the circuit of the pole changer relay at contact 297 before it is closed at contact 154 which 40 would not occur until the operator withdraws the calling plug.

In addition to the electrically controlled apparatus here shown in the cord circuit, there is associated with each operator's cord 45 circuit a special signaling key 165, normally open and connected between the free side of battery B^2 and the conductor 164 of the calling supervisory circuit by way of conductors 167 and 166 respectively. The function 50 of this key is to control the pole changer relay associated with another cord circuit, when the cord circuit with which the key is associated is connected with any one of the multiple jacks of either of two subscribers 55 inter-connected through the said other cord circuit.

The effect of the closure of the special key 165 is to short circuit or shunt out the windings of its associated relay 153 and that 60 of the other operator already connected with the same wanted line. This shunt circuit will be described in detail in the course of the operation which follows.

In operation the subscriber at substation 65 E desiring a connection with a subscriber

at substation F, signals the operator by raising his receiver from the switch hook which closes his line circuit and actuates the line relay 105 in a manner similar to that described in connection with Fig. 4, 70 and the operator perceiving the signal inserts the answering plug 126 in the jack 110 which energizes the cut-off relay 102 extinguishing the line signal. The operator then actuates her listening key and ascertaining the number desired to be that of the substation F inserts the calling plug 127 in the jack 124 whereupon the cut-off relay 119 is connected in series with the calling supervisory lamp 150 and relay 153, 80 this circuit being traced as follows: Battery B^2 , 107, 106, 302, 153, 150, 164, 161, 163, 119, 120, 367, and 104 back to the grounded side of battery B^2 . This circuit energizes the relay 153, lamp 150 and cut-off 85 relay 119. The energization of relay 153 opens the circuit of the pole changer 140 at contact 154 and the energization of the cut-off relay disconnects the called line from the line relay 121. The operator then actuates her ringing key to signal the called subscriber in the usual manner, and when the called subscriber answers by raising his receiver from the switch hook his line circuit is closed energizing the calling supervisory relay 149 which partially closes the circuit of the pole changer relay at contact 197 and shunts out the calling supervisory lamp through resistance 152 and contact 151. The extinguishing of the calling supervisory light indicates to the operator that the connection has been completed and leaves her free to attend to other calls. The energizing circuit of the calling supervisory relay 149 is included in the battery supply 105 circuit of the called subscriber which may be traced as follows: Battery B^2 , 107, 142, 139, 137, 135, 149, 131, 115, through substation F by way of a transmitter, switch hook, induction coil winding, magnet windings of 110 the special signal 301 and back over line wire 116, tip conductor 129, 133, 136, 138, 143, 103 and 104, back to the grounded side of battery. Although this circuit includes the windings of the special signal 115 301, the signal is not actuated at this time as it is so connected in the circuit that the polarized armature will tend to turn in the opposite direction to that in which it is designed to turn in order to effect a signal. 120 Now, should a third subscriber attempt to obtain a connection with either one of the subscribers, for example subscriber F, such third party would obtain a connection with a second operator through her answering 125 plug, corresponding to 126, and the second operator ascertaining the number required to be that of the substation F will test one of its multiple jacks, such as 125, at her position and finding the line busy will in- 130

sert her calling plug, corresponding to the plug 127, into the multiple jack 125, and instead of actuating the ringing key 158 as she would have done had the line not been 5 busy, she operates the special signaling key 165. This last act of the second operator, connects the free end of the common battery B² to the right hand terminal of the relay 153 of the first mentioned operator's cord 10 circuit, over the following paths: Battery B², 167, 165, 166, 164, of the second operator's cord circuit, multiple jack 162, 163, 161, thence through the first operator's cord circuit over conductor 164, resistance 15 152 and the lamp 150 in parallel to the right hand terminal of relay 153. As the other terminal of relay 153 is permanently connected to the free side of battery B² by way of conductors 302 and 107, this 20 relay together with the lamp 150 are shunted out of circuit so long as the key of the second operator remains closed which is momentary. The relay 153 of the first mentioned operator's cord circuit there- 25 upon becomes de-energized releasing the armature 154 and completing the initial energizing circuit of the pole changer relay 140, over the following path: Battery B², 107, 70, 302, 154, 155, 140, 158, 297 and 30 back to battery B².

Energization of relay 140 causes it to attract its pole changer armatures 139, 138 and the locking armature 157. The locking armature closes a locking circuit for 35 the pole changer relay as follows: free side of battery B², 107, 157, 156, 104, 158, 297 and back to the grounded side of battery B². Thus, after the second operator releases the key 165, removing the shunt 40 from relay 153 and allowing it to again become energized, the initial energizing circuit of the pole changer relay is again open at contact 154, the relay remaining energized through its locking circuit. The 45 operation of the pole changer contacts 139, 138 reverses the direction of the battery supply circuit in both of the inter-connected lines E and F, and as each of the polarized signaling devices 301 and 303 are each in- 50 cluded in the battery supply circuit of its substation, these signals are actuated, their parts being adjusted to respond to this change in direction of the supply current. The subscribers E and F, perceiving the ac- 55 tuation of their signals, will then, if the present connection is not an urgent one, hang up their receivers and await the calling of the third party. If, on the other hand, the subscriber E is the party wanted 60 by the third party, the second operator responding to the call of the third party would have inserted her calling plug corresponding to 127 in one of the multiple jacks such as 111 of the substation E, and 65 actuating her key 165 would have shunted

out the relay 148 at the answering end of the first operator's cord circuit. In such case, the relay 148 upon de-energization causes the initial energizing circuit of the pole changer relay to be completed over the 70 following path: free side of battery B², 107, 70, 302, back contact of relay 148, 155, 140, 158, 297 and back to the grounded side of battery B².

The pole changer relay energizing, locks 75 itself and effects a reversal of the battery supply circuit of the inter-connected subscribers, E, F, in the same manner as that before described. At the end of the conversation when the subscribers E, F hang up their receivers, their line circuits open and the first operator is given the disconnected signal in the usual manner through her supervisory lamps, and the calling and answering plugs 126 and 127 are withdrawn. 80 Withdrawal of the calling plug 127 opens the circuit through the ring cord conductor 131, thus de-energizing the calling supervisory relay which opens the circuit of the pole changer relay at armature 297, whereupon the pole changer relay is de-energized and the circuits restored to normal. It will thus be seen that the only act required of the operator to actuate the special signal devices of the inter-connected parties, is to 90 insert the plug after testing and actuate her special key 165, after which he may take down the connection as is usual, upon finding the wanted line busy.

In the modification shown in Fig. 6, the 100 operation and circuit arrangement are similar to that described in Fig. 5 except that the system is here shown adapted to the Kellogg type of cord circuit in a two-wire, multiple, common battery system. In the 105 use of this arrangement the subscribers' substation apparatus may be identically like that of Fig. 5. The change necessary to adapt the system to the Kellogg cord circuit is to add the pole changer relay 213, 110 an extra armature on each of the battery supply relays 204, 205, 216, 217, and the special signaling key 233. In this, as in the foregoing arrangement, the pole changer relay 213 is provided with an 115 armature 22 and a pair of pole changer armatures 211 and 212 and is connected to be controlled by the battery supply relays in a manner which will be clearly set forth in the description and operation.

As the circuit arrangement and operation of the standard Kellogg cord circuit is well known in the art, it is not deemed necessary to here describe the same in detail.

The operation of the arrangement of Fig. 125 6 is as follows: The subscriber G desiring to make connection with line H, raises his receiver from the switch hook, closing the line circuit in the usual manner, which energizes the line relay 173 by current flowing 130

- from the free side of battery B³ over 232, 174, 173, back contact of cut-off relay armature 172 over line wire 170 back over line wire 169 through armature 171 of the cut-off relay, to ground and back to battery B³.
- 5 Energization of the line relay actuates the line lamp 180, and the operator perceiving the signal inserts her answering plug 129 into the calling jack 182 of the line G, whereupon the cut-off relay 298 is energized by current flowing from the free side of battery B³ over 215, 212, 210, 209, 205, 291, 184 and through cut-off relay to ground and back to battery. The cut-off relay attracting its 10 armatures opens the operator's cord conductors 200, 201 directly across the line 170, 169. The operator may now converse with the calling subscriber over any well known form of listening set not shown, and ascertaining the number wanted to be that of the line H, will insert her calling plug into one of the multiple jacks, such as 193, of the line H, whereupon the line relay 299 will be energized in series with the sleeve supply 15 relay 217 in a manner similar to that described for the cut-off relay 198. The operator then signals the called subscriber in the usual manner and when he answers by raising his receiver the line circuit H is closed 20 and the lines G and H are connected for conversation over the circuit indicated in heavy lines. The battery supply circuit for the calling line G may be traced from battery B³, over 215, 212, 210, 209, 205, 291, 184, 193, 25 171 over line wire 169 to the substation and back over line wire 170, 172, 183, 290, 200, and tip supply relay 204, 207, 211, 214, and through ground to battery B³. The battery supply circuit of the line H may be similarly 30 traced through the answering side of the cord circuit, which, of course, includes the tip and sleeve battery supply relays 216 and 217 respectively. If while the lines G and H are thus inter-connected, a third party 35 should attempt to get connection with either one of them, for example the line H, a second operator would become connected with the said third party through the answering side of her cord circuit which 40 would be identically the same as the one shown and supplied from the common battery B³. The second operator would then test one of the multiple jacks of the line H and finding the line busy would insert her 45 calling plug and momentarily close the special signaling key 233. The closure of this key will connect the free side of battery to the right hand terminal of the sleeve battery supply relay 217 of the first operator's 50 cord circuit by way of conductor 232, 231, resistance 234, contacts of key 233 and sleeve contact 293 of the second operator's cord circuit and thence by way of sleeve contact 185 of a multiple jack through the first operator's cord circuit over the sleeve con- 55 ductor 201 to the right hand terminal of the battery supply relay 217. As the other terminal of this relay is connected directly to the free side of battery by way of conductor 209, 210, 212 and 215, it will be shunted out of circuit and become de-energized. De-energization of this relay 217 of the first operator's cord circuit will cause the armature 221 to be retracted, completing the initial energizing circuit of the pole changer 60 relay 213 over the following path: free side of battery B³, 215, 213, 220, 221, 219, 323, 218 and back by way of ground to battery B³. The pole changer relay energizing, locks itself through armature 222 in the following 65 circuit: free side of battery B³, 215, 213, 223, 222, 219, 323, 218 and back to the grounded side of battery. The pole changer relay will thus remain energized over this locking circuit after the key 233 of the second operator is released and the sleeve battery supply relay 217 of the first operator is again energized. The energization of the pole changer relay associated with the cord circuit of the first operator reverses the direction 70 of the battery supply current over both of the previously inter-connected lines G and H, actuating the polarized signaling devices at the respective sub-stations, all in a manner similar to that previously described for Fig. 75 5. Had the third party desired connection with the line G, the second operator would have inserted her calling plug into one of the multiple jacks of the line G, such as 186, and actuating the key 233, would have 80 caused the de-energization of the answering sleeve battery supply relay 205 of the first operator's cord circuit. De-energization of this relay would have completed the initial 85 energizing circuit of the pole changer relay over the following path: free side of battery B³, 215, 213, 220, 320, 323, 319, 321, and back to the grounded side of battery. The locking up of the pole changer relay would have 90 taken place in the same manner and over 95 the same circuits as before described. As the pole changer relay 213 is locked through a front contact of the calling tip battery supply relay 216 of the first operator the reversal of the current in the inter-connected 100 lines will be maintained until the subscribers hang up their receivers and the cord circuit is disconnected from the jacks, whereupon the circuit of the tip relay 216 will be 105 opened at the tip contact 292, and this relay de-energizing will cause the circuit of the pole changer relay to be opened at the front contact of its armature 323, thus restoring 110 the circuits to normal. 115
- It is to be noted that with the circuit arrangement of both Figures 5 and 6 the pole changer relay of the second operator's cord circuit is also operated when she actuates her special signal key in a manner similar in all respects to that described for the operation 120 125 130

of the pole changer of the first operator's cord circuit. This results, of course, in a reversal of the current supply through the second operator's cord circuit and a consequent actuation of the special signal at the substation of the third party, indicating to said third party that the party called is busy and has been notified that a third party is calling. As the pole changer relay becomes de-energized upon the withdrawal of the calling plug, the signal to the third party endures only so long as the operator's calling plug is in the jack, after which the signal is restored to normal and the third party may, if he so desires, call for another number without having to hang up his receiver to get another operator.

The modification shown in Fig. 7 makes use of the same general circuit arrangement, that is, the Western Electric three-wire multiple common battery system, the differences existing only in the cord circuit, the line circuits remaining identically the same. This difference in the cord circuit consists in the omission of the special signaling key and the use of a normally de-energized marginal relay 269 used in place of the relay 153 of Fig. 5 and controlling the initial energizing circuit of the pole changer relay through a normally open contact. The winding of this marginal relay is so adjusted in relation to the strength of the battery and other apparatus, that it will not actuate when connected in series with the cut-off relay 243, as is the case during the interconnection of two lines through the cord circuit under normal conditions.

In the use of this type of cord circuit, the operator always, first, tests the called line by touching the sleeve conductor 240 with the tip of her calling plug 300, which, if the tested line is busy, will give her the usual busy signal through her listening set in the same manner as that described for Fig. 4. At the moment of this test, the grounded side of battery is connected to the sleeve contact 240 through the low resistance of the winding 245 of the repeat coil, and I take advantage of this to operate the marginal relay in the cord circuit of an operator previously connected with the same line, in the manner which will be clearly understood from the description of operation as follows:

Assuming that the cord circuit here shown has its answering and calling plugs inserted into the jacks represented by the sleeve contacts 235 and 240 respectively, and that the called subscriber has answered, the supervisory relays 260 and 261 would be energized in the battery supply circuits of the respective lines, while the cut-off relays 237 and 243 will be energized each in series with its associated marginal relay and lamp shunting resistance. The current at this time passing

through each cut-off relay will not be sufficient in volume to energize the marginal relay. Thus under the condition just described the initial energizing circuit of the pole changer relay will be opened at the front contacts of the marginal relays 265 and 269, and partially closed at a front contact of the armature 273 of the calling supervisory relay 261. However, upon the testing of one of the multiple jacks, such as 241, of one of the interconnected subscribers by a second operator, the winding of the cut-off relay 243 will be shunted by the low resistance winding 245 of the repeat coil of the said second operator, the shunt being as follows: right hand terminal of cut-off relay 243, ground conductor 238, then wire 255, 253, 250, 247, repeat coil winding 245, tip conductor 258, tip contact 300 of the second operator's calling plug, and thence to the left hand terminal of the cut-off relay 243 by way of the multiple sleeve contact, such as 241, and multiple 242. This shunting out of the cut-off relay will effect an increased flow of current through the marginal relay 269 of the first operator's cord circuit and for which increased flow the said marginal relay is adjusted. The increased circuit through the marginal relay is as follows: battery B⁴, 254, 240, 269, branching through 266 and 267 to conductor 276 of the first operator, and there over through ring contacts 277 and 240, multiple 242, and again branching through cut-off relay 243, conductor 238 to ground and through the multiple jack sleeve 241 through the tip side of the second operator's cord circuit to ground by way of tip contact 300, tip conductor 258, 245, 247, 250, 253 and 255.

Energization of the marginal relay completes the initial energizing circuit of the pole changer relay over the following path: battery B⁴, 254, 238, 240, 270, 271, pole changer relay 251, 272, 273, and back to the grounded side of battery by way of conductor 239.

The pole changer relay energizing locks itself in the following circuit: B⁴, 254, locking armature 274, contact 275, 251, 272, 273 and back to the grounded side of battery by way of conductor 239. The pole changer relay being thus locked will remain energized after the second operator removes the tip of her calling plug from the sleeve contact of the multiple jack, resulting in the removal of the shunt from around the windings of the cut-off relay 243, and consequently the de-energization of the marginal relay 269 of the previously connected operator. The energization of the pole changer relay also effects a reversal of the direction of the battery supply circuit in both of the inter-connected lines, through the attraction of its pole changer armatures 249—250, in a manner similar in all respects to that before described for the modification of Fig. 5. Had

the second operator tested a multiple jack, such as 236, of the calling subscriber, the marginal relay 265 of the previously connected operator would have been actuated in 5 a manner similar to that of the relay 269, completing the initial energizing circuit of the pole changer relay through its front or normally open contact and conductor 340, the remainder of said circuit being over the 10 same path as previously described.

After the inter-connected subscribers hang up their receivers, and the operator withdraws her plugs, the calling supervisory relay becomes de-energized in the usual manner, opening the circuit of the pole changer relay at a front contact on the armature 273, thus de-energizing the pole changer relay and restoring the circuits to the normal condition shown in the diagram.

From the foregoing description, taken in connection with the accompanying drawings the advantages of the arrangement of circuits and apparatus and the method of operating, will be readily understood by those skilled in the art to which the invention 25 pertains, and while I have described the principle of operation together with the device which I now consider to be the best embodiment thereof, I desire to have it understood that the device shown is merely illustrative and that such changes may be made as desired as fall within the scope of the appended claims.

What I claim is:

1. In a telephone exchange system, a plurality of substations and talking circuits therefor, connecting links for inter-connecting said substations, means individual to the links operable when connected through 40 its associated link with any one of a plurality of lines already connected through another link to produce current changes in all of said inter-connected lines, and signaling means at said substations responsive to 45 said current changes operable during completion of the talking circuit of its associated substation.

2. In a telephone exchange system, a plurality of substations and talking circuits 50 therefor, connecting links for inter-connecting said substations, means individual to the links operable when connected through its associated link with any one of a plurality of lines already connected through another 55 link to produce current changes in all of said inter-connected lines, and signaling means at said substations responsive to said current changes operable during completion of the talking circuit of its associated substation, together with other signaling means 60 individual to the said substations for initially signaling the subscribers.

3. In a telephone exchange system, a central station, a plurality of substations, line 65 circuits connecting said substations with

said central station, multiple contacts at the central station associated with each of said lines, connecting links at the central station co-operating with said multiple contacts for inter-connecting the lines, means for supplying current through said connecting links to the lines connected therewith, current-controlling means associated with each of said links operable to vary the current supplied to the lines through its associated 75 links, control means associated with each of said links for controlling the current-controlling means of any other link through the multiple contacts of a common line and signaling means at said substations re- 80 sponsive to the variation in current produced by said current-controlling means.

4. In a telephone exchange system, a central station, a plurality of substations, line circuits connecting said substations with 85 said central station, multiple contacts at the central station associated with each of said lines, connecting links at the central station co-operating with said multiple contacts for inter-connecting the lines, means 90 for supplying current through said connecting links to the lines connected therewith, current reversing means associated with said links for reversing the current supplied to a line through its associated link, control 95 means associated with said links for controlling the current reversing means associated with any other link through said multiple contacts, and signaling means at said substations responsive to a reversal of current in the line.

5. In a telephone exchange system, a central station, a plurality of substations, line circuits connecting said substations with 105 said central station, multiple contacts at the central station associated with each of said lines, connecting links at the central station co-operating with said multiple contacts for inter-connecting the lines, means for supplying current through said connecting links to 110 the lines connected therewith, current reversing means associated with said lines for reversing the current supplied to a line through its associated link, control means associated with said links for controlling the 115 current reversing means associated with any other link through said multiple contacts, signaling means at said substations responsive to a reversal of current in the line, and means for maintaining said reversal of current during the closure of the line circuit.

6. In a telephone exchange system, a central station, a plurality of substations, line circuits connecting said substations with 125 the central station associated with each of said lines, connecting links at the central station co-operating with said multiple contacts for inter-connecting the lines, means for supplying current through said connect- 130

ing links to the lines connected therewith, current reversing means associated with said links for reversing the current supplied to a line through its associated link, and operable upon the testing of a line with which its associated link is connected and signaling means at said substation responsive to a reversal of current in the line.

7. In a telephone exchange system, a central station, a plurality of substations, line circuits connecting said substations with said central station, multiple sets of contacts at the central station, associated with each of said lines, each set comprising line contacts and a test contact, connecting links at the central station co-operating with said multiple contacts for inter-connecting the lines, means for supplying current through said connecting links to the lines, a test circuit connected with the test contacts of each line containing a resistance adapted to be shunted upon the testing of the associated line, an electrically operated pole changer associated with each link operable to reverse the current supplied to a line through its associated link, a control relay for said pole changer associated with each link having its energizing circuit included in the test circuit of a given line when its associated link is connected with the said given line, said relay and said resistance being so adjusted that the relay will become energized only upon the shunting of said resistance and signaling means at said substations responsive to a reversal of the said supplied current.

8. In a telephone exchange system, a plurality of substations and line circuits therefor, links for inter-connecting the lines, a source of current supply for said lines adapted to be connected therewith through said links, a pole changer associated with each link and operable to reverse the current in the line supplied

through its associated link, a test circuit 45 for each line, testing means associated with each link adapted to co-operate with said test circuits and produce current changes therein, a relay associated with each link controlling the said pole changer and 50 responsive to current changes in the test circuit of the line with which its associated link is connected, and signaling means at said substations responsive to a reversal of current in the line.

9. In a telephone exchange system, a plurality of substations and line circuits therefor, links for inter-connecting the lines, a test circuit for each line, testing means associated with each link adapted to co-operate 60 with said line test circuits and produce current changes therein and in the test circuit of a link connected therewith, a relay associated with the test circuit of each link responsive to current changes therein and 65 operable to produce current changes in the lines inter-connected through its associated link, and signaling means at said substations responsive to said current changes in their respective lines.

10. In a telephone exchange, a plurality of substations, talking apparatus at each substation, and signaling means at each substation, the signaling means of a given substation being operable upon the connection 75 of a third substation with said given substation when said given substation is busy.

11. In a telephone exchange system, a central office, substations, means for inter-connecting said substations and means associated with said interconnecting means operable upon the connection of a third substation with any one of a pair of substations already connected to signal a plurality 85 of said connected substations independently of said talking apparatus.

NORMAN T. WHITAKER.
